UNITED STATES PATENT OFFICE.

CHARLES C. ATKINSON, OF MIAMI, FLORIDA.

AUTOTRUCK LOADER.

1,411,829.

Specification of Letters Patent. Patented Apr. 4, 1922.

Application filed June 30, 1920. Serial No. 393,163.

To all whom it may concern:

Be it known that I, CHARLES C. ATKINSON, a citizen of the United States, residing at Miami, in the county of Dade and State 5 of Florida, have invented new and useful Improvements in Autotruck Loaders, of which the following is a specification.

This invention relates to an improved loading device for motor trucks and is especially designed for loading logs and heavy 10 articles of similar shape, although it is also applicable to heavy loading in general.

The primary object of the invention is to provide a mechanism of simple and economical construction that can be driven from the engine of the motor vehicle and controlled in a simple and convenient manner.

The invention provides a plurality of 20 drums adapted to rotate in opposite directions, whereby when one log or other object is being loaded on the vehicle a second cable may be attached to another object preparatory to loading. These drums are preferably driven from a shaft actuated by the 25 engine of the motor vehicle, through transmission mechanism which affords a forward and a reverse motion for driving the respective drums. Novel mechanism is also 30 provided for guiding and supporting the cables.

Reference is made in the following specification to the accompanying drawings illustrative of the preferred embodiment of my 35 invention, and in which:—

Figure 1 is a top plan view of the frame of a motor vehicle having my invention applied thereto;

Figure 2 is a transverse section on the 40 line 2—2 of Figure 1 showing a log in the loading operation;

Figure 3 is a perspective view of the mechanism for controlling the shiftable member of the transmission device;

Figure 4 is a section on the line 4—4 of Figure 1;

Figure 5 is a section on the line 5—5 of Figure 1 looking in the direction of the arrows, and

Figure 6 is a section through one of the drums showing the ratchet drive between the auxiliary shaft and the drum.

The numeral 10 designates the frame of a motor truck having the body 10', the usual hood 11 concealing the engine, and the usual steering wheel 12 having associated there-

with the spark and throttle controls 13 and 14. The numeral 15 designates the driver's seat. The engine of the vehicle drives through the main clutch (not shown), the main drive shaft 16 to the transmission mechanism 17 and differential 18 mounted on the rear axle. In the illustrated form of my invention the transmission mechanism 17 is shown as mounted on the rear axle 60 housing and in this case the drive for the loading mechanism is taken directly from the main shaft 16 by means of the sprocket wheel 19 secured thereto, and a sprocket wheel 20 secured to a counter-shaft 21 of an auxiliary transmission mechanism.

A sprocket chain 22 connects the two sprocket wheels 19 and 20. Gear 23 and pinion 24 are also secured to the countershaft 21 in spaced relation and intermediate the 75 transverse supporting frame members 25 and 26, which are secured to the side members of the truck frame. The counter-shaft 21 and an auxiliary shaft 27 are rotatably mounted on these transverse frame members 80 25 and 26 by means of detachable bearing plates 28 and 29. An idler pinion 30 is mounted on the stub shaft 31, which is supported on the transverse member 25 by means of a bearing plate 32. The auxiliary 85 shaft 27 is splined as shown at 33 and a gear set comprising integral gears 34 and 35, and a grooved collar 36 is mounted thereon. The gear 35 is adapted to operatively connect the gear 24 to the shaft 27 in order 90 to drive the same in a forward direction, and the gear 34 is adapted to mesh with the idler wheel 30 in order to drive the shaft 27 in a reverse direction, it being understood that the position of the gear set intermediate 95 of the gear 24 and idler 30 will give a neutral or non-driving relation. The gear set is shifted to these various positions of forward, neutral or reverse by means of a forked member 37 adapted to engage with- 100 in the groove 36 of the gear 35.

The member 37 is secured to a rod 38 which is shiftable longitudinally in bearings 39 and 40 detachably secured respectively to the transverse frame members 25 and 26. 105 The rod 38 is connected to the transverse shaft 41 journalled on bearings secured to the side members of the frame 10, by means of a link 42 having a loop portion embracing the rod 38 and adapted to engage the head 110 43 formed on one end of the rod, an arm 44 secured to the shaft 41 and a link 45 which

is pivotally secured to the arm 44 and link 42. An operating arm 46 is secured to one end of the transverse shaft 41 and is connected at its opposite end to a pivoted control lever 47 by means of the rod 48.

Two drums designated respectively as 50 and 51 are rotatably mounted on a cylindrical extension of the auxiliary shaft 27.

The drums are formed with end flanged portions 52 and 52', the portion 52 having a ratchet wheel 53 detachably secured thereto by means of fastening devices 54. A collar 55 is keyed to the shaft 27 adjacent to the flanged portion 52 and ratchet pawls 56 are pivotally mounted thereon by means of the pivot pins 57. Springs 58 secured at one end to the collar 55 are adapted to bear against the pawls 56 in order to maintain them in engagement with the teeth of the ratchet wheel 53. The collar 55' cooperating with the flanged portion 52' of the drum 51 is similar to the collar 55 previously described and is keyed to the shaft 27, but the pawls 56' are pivoted thereto so as to operatively engage the oppositely disposed teeth of the ratchet wheel 53', detachably secured to the flange portion 52'. From this ratchet construction it will be apparent that one drum will be rotated when the shaft 20 rotates in one direction while the remaining drum will be rotated when the shaft 25 moves in the reverse direction.

A cable 60 is wound upon the drum 50 in such direction that the rotation of the drum from the shaft 27 will result in the further winding of the cable on the drum. A cable 61 is wound upon the drum 51 in such direction that the rotation of said drum through the auxiliary shaft will result in this cable being wound upon the drum. In other words the cables 60 and 61 are wound on their respective drums in opposite directions. In order to guide the cable 60 so that it may exert a pull in the desired direction upon the objects to be loaded, a sheave 62 is pivoted at 63 to the body 10' of the truck and a second sheave 64 is pivoted to the upper end of the beam 65.

The beam 65 is mounted in the bracket 50 secured to a side member of the body 10'. Angle plates 67 and 68 are secured to the upper and lower ends of the beam, one arm of each angle plate contacting with an end of the beam and projecting beyond the same, the projecting portions being provided with aligning apertures for receiving the threaded ends of the reinforcing rod 69. A nut 70 secured to the upper threaded end of the rod and a nut 71 secured to the lower threaded end of the rod maintain said rod in position. A tie rod 72 is made in sections adjustably connected together by means of turn buckle 73. One of the apertured ends of the tie rod 72 is interposed on the rod 69 between the nut 71 and the arm of the angle

plate 68. The other end of the tie rod is secured to the channel frame 10 of the truck by suitable fastening devices 74. It will be noted that the cable 60 passes over sheaves 62 and 64, and the free end of the cable is provided with a hook 75 whereby a loop may be formed in one end of the cable for engaging the log or other object to be loaded. The block 76 preferably in form of a wedge is driven between the bracket 66, 75 and the reinforcing rod 69 in order to maintain said rod under tension. The pull on the cable 60 and tie rod 72 is such as to exert a tensile stress which is resisted by the beam 65 and the rod 69. The log 77 is adapted 80 to slide on spaced skids 78 supported by means of inclined posts 80 inserted within the tapered brackets 81. As shown in the drawings both of the brackets 81 are carried by the frame of the truck. However, 85 it will be understood that one or both of said brackets may be carried by the frame of a trailer indicated by the dotted lines 82 in Fig. 1. Of course when the loading operation is first started the skids 78 may rest 90 directly upon the body of the truck, but as the load on the truck increases in height the post 80 may be utilized for lifting one end of the skids to the desired height. When the vehicle is in motion the brackets 66 and 95 81 are used to support the ordinary staves which retain the load upon the body of the vehicle.

In operation the transmission mechanism of the vehicle is first placed in neutral position, the main clutch being in driving position so that the engine of the vehicle may drive the main shaft 16, but the motion thereof is not communicated to the rear wheels 83 of the truck. Motion is transmitted from the shaft 16 to the counter-shaft 21 by means of the sprocket chain 22 and from the counter-shaft 21 the motion is communicated to the auxiliary shaft 27 through the forward drive pinion 24 and gear 35, or through the reverse drive, namely, gear 23, idler 30 and pinion 34. The gear set 34 and 35 may also be placed in neutral position in which case no motion will be communicated from the counter-shaft 21 115 to the shaft 27.

Assume that the gear set is in the neutral position as above described. The free end of the cable 60 is then pulled so that the cable will unwind from the drum 50 and a 120 loop is formed around a log 77 as shown in Figure 2. The gear 35 is then shifted so as to engage pinion 24 and drive the shaft 27 and drum in a forward direction, which results in winding the cable 60 on the drum 125 50 and drawing the log 77 up the skids 78 and into the body of the vehicle. While this operation is continuing the free end of the cable 61 is drawn so as to unwind the same from the drum 51 and attached to the log 130

next to be loaded. It will be seen that this method of operation affords an almost continuous loading operation. When the log 77 has been loaded on the vehicle the gear 5 set 34 and 35 is shifted so as to engage the pinion 77 and drive the drum 51 in a reverse direction, which results in the winding of cable 61 upon the drum and the loading of a second log. While this second log is being 10 loaded the free end of the cable 60 is detached from the log 77 originally loaded and attached to the third log and so, until the loading of the vehicle is completed.

This invention has been described in connection with a motor vehicle having the transmission mechanism mounted on the rear axle. However, it will be understood that it is equally adapted to motor vehicles utilizing the unit power plant, or having 15 the transmission mechanism located near the center of the vehicle. In such cases, however, the driving mechanism 22 will be modified accordingly and preferably the drive will be taken from the jack shaft which is 20 ordinarily provided in the transmission mechanism of modern motor trucks for actuating auxiliary mechanisms such as a loading device. Other modifications may 25 also become apparent to those skilled in the art to which this invention appertains, but all variations in the details of construction of my invention which do not depart from the spirit or scope of the appended claims 30 are included within the purview thereof.

35 I claim:

1. The combination with a truck having a frame with a motor mounted therein, of a log loading device, skids for guiding the logs during the loading operation, means 40 for supporting one end of said skids on the truck frame, cables for engaging logs to be

successively loaded, a drum for each of said cables, and means driven by said motor for selectively actuating said drums in opposite directions.

2. The combination with a truck having a frame with a motor mounted therein, an auxiliary shaft mounted in said frame having a drum mounted thereon, a sheave pivoted to a side member of said frame, a 50 bracket secured to said frame, a beam mounted in said bracket, a sheave pivoted to one end of said beam, a tie rod connecting the other end of said beam to said frame, a cable passing over said sheave and wound 55 on said drum and means for driving said auxiliary shaft and drum from said motor.

3. In combination with the frame of a motor truck, a bracket secured to said frame, a beam supported in said bracket, 60 angle plates secured to each end of said beam having aligning apertures formed therein, a reinforcing rod passing through said apertures in spaced relation to the bracket, a block interposed between said 65 bracket and rod, a tie rod secured to one of said angle plates and the frame, a sheave pivoted to the other of said angle plates, a cable passing over said sheave, said sheave and tie rod exerting forces on said angle 70 plates tending to place tension on said reinforcing rod, a drum for winding said cable, and mechanism actuated by the engine of the motor truck for rotating said drum.

In testimony whereof I have hereunto set 75 my hand in presence of two subscribing witnesses.

CHARLES C. ATKINSON.
